VACUUM CLEANER NOZZLE

Johan Arne Dömsedt, Hagersten, and Knut Yngve Karlsson, Skarholmen, Sweden, assignors to Aktiebolaget Electrolux, Stockholm, Sweden, a corporation of Sweden

Filed Apr. 5, 1968, Ser. No. 11,312

Claims priority, application Sweden Oct. 13, 1967

Term of Patent 14 years

Int. Cl. D4—01

U.S. Cl. D49—19

FIG. 1

FIG. 2

FIG. 3

FIG. 4

FIG. 5

FIG. 6

FIG. 7

FIG. 1 is a front perspective view of a vacuum cleaner nozzle showing our design;

FIG. 2 is a rear perspective view with the nozzle inverted from the position shown in FIG. 1;

FIG. 3 is a side elevational view with the nozzle in the position shown in FIG. 1;

FIGS. 4 and 5 are front and rear elevational views, respectively, with the nozzle in the position shown in FIGS. 1 and 3;

FIG. 6 is a plan view from above with the nozzle in the position shown in FIGS. 1, 3, 4 and 5; and

FIG. 7 is a plan view from below with the nozzle in the position shown in FIG. 2.

We claim:

The ornamental design for a vacuum cleaner nozzle, as shown.
